UNITED STATES PATENT OFFICE.

SANFORD D. LELAND, OF WINCHESTER, MASSACHUSETTS, ASSIGNOR TO MANUFACTURING, EQUIPMENT AND ENGINEERING COMPANY, OF SOUTH FRAMINGHAM, MASSACHUSETTS, A CORPORATION OF MASSACHUSETTS.

METALLIC STOOL OR CHAIR.

1,073,860.

Specification of Letters Patent. Patented Sept. 23, 1913.

Application filed January 20, 1910. Serial No. 539,026.

To all whom it may concern:

Be it known that I, SANFORD D. LELAND, a citizen of the United States, residing at Winchester, county of Middlesex, and State 5 of Massachusetts, have invented an Improvement in Metallic Stools or Chairs, of which the following description, in connection with the accompanying drawing, is a specification, like characters on the drawing 10 representing like parts.

This invention relates to stools or chairs which are especially designed for use in factories, shops, stores, etc., and it has for its object to provide a novel metal stool or chair 15 which can be inexpensively manufactured and which is stiff and rigid and well adapted to withstand the more or less severe usage to which stools in factories or shops are subjected.

Referring to the drawings, Figure 1 is a 20 side view of a stool embodying my invention; Fig. 2 is a front view thereof; Fig. 3 is an enlarged section on the line $x-x$, Fig. 1; Fig. 4 is an enlarged section on the line 25 $y-y$, Fig. 1; Fig. 5 is a section through the seat of the stool showing an all-metal construction; Figs. 6 and 7 are similar views showing a stool seat formed partially of wood or other material; Fig. 8 is an enlarged plan view of one of the feet of the 30 stool; Fig. 9 is a section on the line $a-a$, Fig. 8; Fig. 10 is an enlarged view of the upper portion of one of the legs.

The stool herein illustrated is a three-legged stool, but the invention may also be embodied in a stool or chair having four or any other number of legs. The seat of the stool is shown at 3 and the legs at 4. The legs are made of angle-iron and may be conveniently connected together by suitable 35 braces 5. At the lower ends the legs are preferably bent outwardly and the angle of the angle-iron is flattened so that the legs will present at their lower ends comparatively flat feet 6 adapted to rest on the floor. The seat 3 may be made entirely of metal or may be made partially of metal and partially of wood, fiber and similar material. Where the seat is made entirely of metal, I 40 propose to shape it by means of dies from sheet metal, so as to present the top 7 and the annular flange 8, and in shaping the seat the dies will be so constructed as to form indentations or grooves 9 in the flange.

8. The upper end 10 of each angle-iron leg 55 is flattened or spread, as shown in Figs. 3 and 10, and this flattened portion 10 is secured to the inside of the flange 8 by suitable rivets 11. In flattening the angle-iron it is not practicable to eliminate entirely the apex or ridge of the angle, and as a result after the end of the leg is flattened, it will have a rib 12 on the exterior which forms a continuation of the corner of the angle. The indentations or grooves 9 are preferably 60 made of such a shape and size as to approximately fit this rib or corner 12, and the flattened portion 10 of the angle-iron is given a proper curvature to fit the inside of the flange 8. When the parts are assembled the 65 rib 12 of the flattened portion of the leg enters and fits into the groove or indentation 9 in the flange 8, and when the leg is riveted to the flange 8, this interlocking of the flange and leg makes the stool very stiff 70 and rigid.

I may make the top of the stool as shown in Figs. 6 and 7, that is, with the central portion of the top of wood or fiber. In Fig. 6 the center portion of the seat or top 80 is cut out and the material at the end of the aperture is bent downwardly and laterally to form the inwardly-extending flange 14 which is situated out of and below the plane of the top of the seat. This 85 flange 14 constitutes a rest on which a filling 15 of wood, fiber or similar material may be supported, as shown in Fig. 7, said filling portion being preferably riveted or bolted to the flange 14, as shown at 16. 90

In Fig. 6 I have shown a construction wherein the filling 17 of the seat is made of fiberoid or some similar material that may be molded in position. In this embodiment the seat 3 after having been formed 95 as shown can be placed in a mold and the mold may be filled with the plastic material from which the seat is formed, this material being forced around the annular flange 14 so that when it hardens it will 100 be interlocked with the flange, as clearly seen in Fig. 6. In this way a stool may be produced which has a wooden or fiberoid seat, but which has all the advantages due to the metallic construction.

If it is desired to provide the stool with a back, this may be done by securing the back 20 to an angle-iron arm 21 which is

properly shaped, and the lower end of which is secured to one of the legs by bolts or rivets 22, as clearly seen in the drawings. In some places, such, for instance, as in offices and stores, it is desirable to provide the feet of the stool or chair with tips which will prevent the feet from scratching the floor. I have herein shown tips 25 of rubber or some similar material, each of which is provided with the head portion 26 of a shape to receive a foot of the stool leg. This head portion 26 not only fits the under side of the leg but is preferably provided with a vertically-extending flange 27 which embraces the end of the leg 6. Each tip may be secured to the leg by means of rivets or fastenings 28.

The construction I have herein illustrated is very simple and one which admits of rapidly assembling the parts of the chair. In addition, the peculiar way in which the legs are secured to the seat makes a very strong and rigid construction and one which is well adapted to withstand severe usage.

Having fully described my invention,

what I claim as new and desire to secure by Letters Patent is:—

In a stool or chair, the combination with a seat formed wholly or partially of sheet metal bent or shaped to present an annular depending flange provided on its interior face with vertical grooves or indentations, of angle iron legs each arranged with the apex of the angle directed outwardly and each having its sides at the upper end spread sufficiently to lie against and fit the interior of said flange while leaving the apex or corner of the angle in the form of a rib which projects beyond the outer face of the spread sides, said rib entering and fitting one of the grooves or indentations, and means securing said spread sides of the angle to the flange.

In testimony whereof, I have signed my name to this specification, in the presence of two subscribing witnesses.

SANFORD D. LELAND.
